Assistant Examiner — Anthony Vincent Rotolo

(57) **CLAIM**

The ornamental design for a lamp as shown and described.

DESCRIPTION

1. Lamp
2. Lamp
3. Lamp
- 1.1 : Perspective
- 1.2 : front, opposite back side being a mirror image thereof
- 1.3 : left, opposite right side being a mirror image thereof
- 1.4 : Perspective
- 1.5 : Bottom
- 1.6 : Top
- 1.7 : Perspective
- 2.1 : Perspective
- 2.2 : front, opposite back side being a mirror image thereof
- 2.3 : left, opposite right side being a mirror image thereof
- 2.4 : Perspective
- 2.5 : Bottom
- 2.6 : Top
- 2.7 : Perspective
- 3.1 : Perspective
- 3.2 : front, opposite back side being a mirror image thereof
- 3.3 : left, opposite right side being a mirror image thereof
- 3.4 : Perspective
- 3.5 : Bottom
- 3.6 : Top
- 3.7 : Perspective

The lamps to be protected all consist of a round shape with
flat cone shaped top and bottom and a stripe through the
front and back.

1 Claim, 21 Drawing Sheets
